UNITED STATES PATENT OFFICE.

MURTAGH J. STRAIN, OF NEW YORK, N. Y., ASSIGNOR TO EMMA R. STRAIN,
OF SAME PLACE.

CIGAR-CASE.

SPECIFICATION forming part of Letters Patent No. 474,613, dated May 10, 1892.

Application filed May 13, 1891. Serial No. 392,570. (No model.)

To all whom it may concern:

Be it known that I, MURTAGH J. STRAIN, a citizen of the United States, residing at New York, in the county of New York and State of New York, have invented certain new and useful Improvements in Cigar-Cases; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to cigar-cases for holding partially-consumed cigars; and it has for its object to construct the case, which is especially adapted for pocket use, so that the cigar can be inserted and held in the same and carried in the pocket without breaking the lighted or burned end of the cigar and without the odor of the cigar being imparted to the clothes of the person.

To the accomplishment of the foregoing objects the invention consists in the construction and combination of parts hereinafter particularly described and then claimed.

The invention will now be fully described, and then claimed, reference being had to the accompanying drawings, forming a part hereof, and in which—

Figure 1 is a vertical section illustrating the preferred form of the case. Fig. 2 is a similar view to Fig. 1 with the cigar shown in position. Fig. 3 is a cross-section on the line xx of Fig. 1. Fig. 4 is a vertical section illustrating a modified form of the invention.

In the drawings the letter A designates the base or lower portion of the case, which is formed at its mouth with the flange B, and over this flange there will fit the cap or cover C, so that when the two are together the external surfaces will be flush with each other and there will be no projecting edge to catch in any other object that may be in the pocket.

Within the lower portion A of the case there is secured, either to the sides or the bottom thereof, but preferably to the bottom, a series of spring or elastic fingers D. These fingers are made to converge toward each other in the direction of their outer ends, and at such

ends are turned or curved outwardly, as illustrated, and are made to terminate at the open end of the section in which they are secured and are separated at that end. By thus forming the fingers the maximum of both strength and firmness of elasticity is imparted to them. It will be observed, also, that the fingers next to the mouth of the case are free and disconnected, so that they will yield at once to the insertion of the mouth end of a cigar and readily accommodate or adjust themselves to the cigar whatever its diameter may be. These springs or clasps are elastic enough to yield to the pressure of the cigar without injuring it, and yet they have firmness enough to hold it securely against accidental dislodgment.

If the fingers had their free ends toward the closed end of the box and were connected together at their outer ends by a band, there would be stiffness instead of elasticity at the mouth of the box, thereby necessitating the insertion of the cigar quite a distance into the box to reach the elastic portion of the fingers. Furthermore, the insertion of the lighted end between the fingers would result in breaking the wrapper at that end, as it would be dry and crisp, and also in the knocking of ashes from the cigar, and as the mouth end would be moist the ashes would adhere thereto and the inconvenience therefrom would be great; but by having the ends terminate at the open end of the section and separated from each other and rendered elastic at that end the lighted end never comes in contact with the fingers or with any part of the case, as the mouth end of the cigar comes between the fingers, while the lighted end projects centrally therefrom and extends into the cap without coming in contact with any part thereof. As a consequence the lighted end is not in any degree injured and does not have even so much as the ashes knocked off.

The cigar may be inserted while still burning, and when the cap is applied the case is made air tight, so that the fire is soon extinguished, while at the same time the odor of the tobacco is confined within the case.

The case is illustrated as of cylindrical form

in cross-section, but may be of any other form desired, and it may be of metal or any suitable material.

Having described my invention and set forth its merits, what I claim is—

The cigar-case composed of the two hollow sections adapted to fit one to the other and the spring-fingers contained within one section and having free open ends terminating at the open end of the section in which they

are secured, the lower ends of the fingers being secured to the inside of the shell, substantially as and for the purposes described.

In testimony whereof I affix my signature in presence of two witnesses.

MURTAGH J. STRAIN.
